United States Patent Office

Des. 212,616
Patented Nov. 5, 1968

212,616

TAPE TRANSMITTER

Louis Lucien Lepoix, Baden-Baden, Germany, assignor to
International Standard Electric Corporation, New York,
N.Y., a corporation of Delaware

Filed Sept. 12, 1966, Ser. No. 3,809

Claims priority, application Germany Mar. 15, 1966

Term of patent 14 years

(Cl. D26—5)

Fig.1

Fig. 2

FIGURE 1 is a perspective view taken from the front top and right side of a tape transmitter showing my new design; and

FIGURE 2 is a perspective view taken from the rear, top and left side thereof.

I claim:

The ornamental design for a tape transmitter, substantially as shown.
